UNITED STATES PATENT OFFICE.

ETIENNE PLANCHE, OF FLINT, MICHIGAN.

ADJUSTABLE HINGE.

1,218,696.

Specification of Letters Patent. Patented Mar. 13, 1917.

Application filed December 11, 1916. Serial No. 136,329.

To all whom it may concern:

Be it known that I, ETIENNE PLANCHE, a citizen of the United States, and resident of Flint, in the county of Genesee and 5 State of Michigan, have invented certain new and useful Improvements in Adjustable Hinges, of which the following is a specification.

My invention relates to hinges and has 10 particular reference to a novel adjustable hinge for automobile doors.

It is well known that difficulty is experienced not only in hanging automobile doors but in retaining the doors in proper adjustment relative to the door-opening after 15 they have been properly hung. The racking strains to which the body is subjected, the exposure thereof in all kinds of weather and the strains imposed on the hinges due to 20 forcible opening and closing of the doors all operate against a perfect fit of the doors or even such exactness as will prevent rattling, uncertain latching, etc.

Having all this in mind, I have devised 25 a hinge which may be very cheaply produced and which is of such simple construction that an unskilled person may manipulate the same to adjust a door. Realizing 30 the necessity for many different adjustments, I have provided for limited universality of movement, securing all the parts, however, by a single fastening bolt.

The invention will be more readily understood by reference to the accompanying 35 drawings, wherein—

Figure 1 is a transverse sectional view on the line 1—1 of Fig. 2, showing a hinge constructed in accordance with my invention;

Fig. 2 is an elevation thereof;

Fig. 3 is a fragmentary elevation showing the form of connection of the strap to the wall or body;

Fig. 4 is a sectional view on the line 4—4 40 of Fig. 3; and

Fig. 5 is an elevation of one of the socket members.

The device is shown as forming a hinge connection between a door 10 and a wall 11. 50 The hinge is composed of two straps or leaves 12, 13, having a hinge connection at 14. The free end of the strap 12 is secured by means of screws 15 to the door 10. In order to permit of the necessary adjustment, the strap 13 is secured to the wall 11. 55 by a novel means which comprise the essence

of this invention. It will be seen that the strap 13 terminates in a bulbous enlargement in the form of a double truncated sphere having a transverse axial opening. 60 The enlargement 16 is directly engaged by the socket or bearing members 17, 18, which engage the inner and outer sides respectively of the enlargement. As shown in Fig. 5, these socket members are in the form of a 65 ring having an axial opening 19, the metal of the ring surrounding the opening being shaped to conform to the periphery of the enlargement 16. The ring is reduced in thickness at 20 in order to accommodate the 70 strap 13. The rings are fitted loosely within a recess formed in the base member 21, these being secured to the wall by means of screws 22. As a means for rigidly holding the strap in adjusted positions, I provide 75 the adjusting bolt 23, having screw-threaded engagement with the base member 21, the head of the bolt bearing upon the outer socket member 18. The shank of the bolt passes through the elongated aperture 24 in 80 the enlarged end 16. It will be seen that clearances are provided at all points and therefore that universality of movement is possible. Therefore, the door which is supported by the hinge may be accurately adjusted and secured in adjusted position by 85 tightening the fastening bolt 23.

The particular advantage from a construction standpoint is in that the adjustments are all made by a single bolt and that this bolt is in such position as to be readily accessible. Furthermore, the construction is extremely simple and economical in manufacture.

It will be understood also that although 95 I have illustrated the adjusted member as being mounted in the wall that this might readily be modified to the extent of connecting the same to the door or by providing adjustments in both connections.

I claim:

1. In a door hinge, the combination of a pair of leaves having a hinge connection, means for rigidly fastening one of said leaves, and means for adjustably fastening the other of said leaves, said last-named means including an enlargement on said leaf, said enlargement having a curved periphery and being transversely apertured, a clamping member adapted to engage said enlargement, and a bolt engaging said clamping member and passing through said

- aperture, said bolt being of a less size than said aperture, whereby said strap may be adjusted relative to the bolt, substantially as described.
5. 2. In a device of the class described, the combination of a pair of hinged straps, the free end of one strap having an enlargement provided with a generally spherical peripheral surface, a clamp engaging the periphery of said enlargement, and a fastening bolt engaging said clamp and adapted to hold the parts in adjusted position.
10. 3. In a device of the class described, the combination of a leaf of a hinge, the terminal portion of which is bulbous and transversely apertured, a pair of clamp members engaging opposite sides of said bulbous end, a base having an aperture for the accommodation of said clamps, and means coöperating with said base and passing through the aperture in said end for rigidly holding the parts in adjusted positions.
15. 4. In a device of the class described, the combination of a pair of hinged straps, the end of one strap being enlarged and having curved side faces, a pair of seat members
- having surfaces curved to coöperate with said side faces, a base member within which said seat members are adjustably mounted, and means for securing the parts in adjusted position, substantially as described.
5. Means for adjustably mounting automobile doors, including, in combination, a pair of hinged straps and means for connecting one of said straps to a support in such manner as to permit of limited universal movement, said means including an end portion having curved sides, a pair of clamps having curved seat portions engaging said curved sides, said end portion and clamps having registering apertures and a bolt of a size materially less than the size of said apertures, said bolt being adapted to pass through the apertures, engage said support and rigidly hold the parts in engagement therewith.
30. 35. 40. 45. Signed at Flint, Michigan, this 6th day of December, 1916.
- ETIENNE PLANCHE.
